Filed Apr. 15, 1968, Ser. No. 11,455

Term of patent 14 years

Int. Cl. D24—02

U.S. Cl. D16—2

FIG. 1.

FIG. 2.

FIG. 3.

FIG. 4.

FIG. 1 is a front perspective view of a housing for a low temperature R-F reactor unit, showing my new design;

FIG. 2 is a front perspective view of the housing for a low temperature R-F reactor unit of FIG. 1 with the top of the case in an open position;

FIG. 3 is a partial sectional view on line 3—3 of FIG. 2; and

FIG. 4 is a partial detailed view of the foraminous portion of the top of the case shown in FIGS. 1 and 2.

The left side of the unit is the same as the right side, as shown in FIGURES 1 and 2.

The rear of the unit is plane, unornamented.

The broken lines are shown for illustrative purposes only.

I claim:

The ornamental design for a housing for a low temperature R-F reactor unit, substantially as shown and described.
